Primary Examiner — Karen E Kearney(74) Attorney, Agent, or Firm — Banner & Witcoff, Ltd.(57) CLAIM

The ornamental design for a display screen with icon, as shown and described.

DESCRIPTION

FIG. 1 is a front view of a display screen with icon showing the new design;

FIG. 2 is a front view of a display screen with icon showing an alternative embodiment of the new design;

FIG. 3 is a front view of a display screen with icon of FIG. 1 shown on a device; and,

FIG. 4 is a front view of a display screen with icon of FIG. 2 shown on a device.

The broken line showing of the remainder of the display screen and the remainder of the device having the display screen in FIGS. 3-4 is for environmental purposes only and forms no part of the claimed design.

1 Claim, 4 Drawing SheetsFIG. 1

FIG. 4
